(57) **CLAIM**

The ornamental design for the battery charger, as shown and described.

DESCRIPTION

FIG. 1 is a perspective view of the battery charger of the invention;

FIG. 2 is a top plan view of FIG. 1;

FIG. 3 is a bottom plan view of FIG. 1;

FIG. 4 is a front side elevation view of FIG. 1;

FIG. 5 is a back side elevation view of FIG. 1;

FIG. 6 is a right side elevation view of FIG. 1;

FIG. 7 is a left side elevation view of FIG. 1; and,

FIG. 8 is a perspective view of the battery charger of the invention in open position.

The broken line disclosure of unclaimed environmental structure shown in the drawings is for illustrative purposes only and does not constitute a part of the claimed design.
